[57] CLAIM

The ornamental design for a shower foot rest, as shown and described.

DESCRIPTION

FIG. 1 is a perspective view taken from the top, front and left side of a shower foot rest showing my new design;

FIG. 2 is a front elevational view showing the shower foot rest in a closed position;

FIG. 3 is a rear elevational view of FIG. 2;

FIG. 4 is a right side elevational view of FIG. 2, the left side being a mirror image of the right side;

FIG. 5 is a top plan view of FIG. 2;

FIG. 6 is a bottom plan view of FIG. 2; and,

FIG. 7 is a vertical cross sectional view of FIG. 1.

The fragmentary broken line representation of a shower stall and the broken line representation of a person in FIG. 1 is for purposes of illustration only and forms no part of the claimed design.

It is to be understood that the pattern of dimples shown in FIGS. 1 and 2 are continuous through out the area indicated.
